UNITED STATES PATENT OFFICE

2,380,853

METHOD OF PRODUCING AROMATIC HYDROCARBONS

Norman F. Linn, Mountainside, and Carl O. Tongberg, Westfield, N. J., assignors to Standard Oil Development Company, a corporation of Delaware

Application August 29, 1942, Serial No. 456,674

4 Claims. (CL. 260—668)

The present invention relates to improvements in the manufacture of aromatics from petroleum sources and, more particularly, it relates to the conversion of naphthas to aromatics, including toluene. Prior to our invention, others have converted normal paraffins and aliphatics, generally, to aromatic compounds employing catalysts such as oxides of the VI group of the periodic system. Cyclization and aromatization of paraffins and olefins is, therefore, a matter of record. The commercial operations, however, with which we are aware generally relate to the conversion of a substantially pure compound, such as normal heptane, to toluene by cyclization and aromatization in the presence of a suitable catalyst. Obviously the amount of toluene produced by such a process from a given quantity of oil containing normal heptane is limited by the narrowness of the boiling range of the charging stock.

According to our process, we are enabled to obtain a greater yield of aromatics from a given original feed stock than has been obtainable heretofore, as will more fully appear hereinafter.

The main object of our invention is directed toward producing a maximum quantity of aromatics from a hydrocarbon oil, such as a naphtha fraction.

Other and further objects of our invention will appear from the following more detailed description and claims.

This invention is especially applicable to the production of maximum quantities of aromatics from relatively narrow boiling range hydrocarbon fractions. In the description which follows the hydrocarbon feed comprises a fraction boiling between about 190° and 240° F. by the Engler distillation procedure and contains such hydrocarbons as toluene, methyl cyclohexane, dimethyl cyclopentane, heptanes and the like.

In the accompanying drawing, we have shown diagrammatically a flow plan illustrating a preferred modification of our invention.

Referring in detail to the drawing, feed stock comprising a naphtha (virgin or cracked) boiling within the range of from 190 to 240° F., is discharged into the system through line 1 and after suitable heating is discharged into a solvent extraction zone 3 where it is subjected to solvent extraction. The oil entering the extraction column is in vapor form and has a temperature of 200 to 235° F. The solvent which may be liquid phenol or the like at a temperature of about 200-220° F. is discharged into the top of the column through line 5 and flows downwardly and

countercurrently to the rising vapors. The effective solvent/oil ratio in the tower is from about 1 to 1, to 8 to 1 by volume.

From the top of the column 3 normally gaseous hydrocarbons such as methane, ethane, propane, and pentane and the corresponding olefins are withdrawn through line 10, and these substances may be processed in any desired manner to convert them to valuable products. Thus, they may be subjected to alkylation where say an isoparaffin is reacted with an olefin, or the normal butanes may be dehydrogenated to form intermediates such as butadiene useful in synthetic rubber synthesis, or the products may be otherwise disposed of in known manner. A side fraction which is largely paraffinic but may contain some olefins is withdrawn as a raffinate through line 12. A portion of this stream may be returned as reflux through line 11. The products stream is then heated in a furnace or the like 14 to a temperature of from 280 to 350° F., then discharged through line 15 into a flash tower 18 from which the overhead product comprising substantially paraffins is withdrawn through line 20. In the case where a solvent such as phenol or another high boiling solvent is present in extraction tower 3, the solvent carried over with the raffinate phase in line 12 may be separated in flash tower 18 and withdrawn through line 22. The paraffins in line 20 are discharged into a cyclization and aromatization zone 25 where they are subjected to temperatures of within the range of from 750 to 1200° F. and pressures of 50 to 400 lbs. per square inch. Cyclization and aromatization vessel 25 contains a catalyst preferably disposed on a foraminous tray T. The catalyst may consist of Cr₂O₃ supported on Activated Alumina, or it may consist of metallic nickel, or it may consist of chromium oxide or gel or simply oxides of chromium, vanadium, titanium, thorium, and cerium deposited on alumina or magnesia. These catalysts are known to the art. To repress coke formation we prefer to charge to reactor 25 via line 41-a and line 24 a quantity of hydrogen or hydrogen-containing gas.

As to feed rates, the paraffins undergoing cyclization are fed to unit 25 at a rate of from 0.1-5 liquid volumes per volume of catalyst per hour, with a feed rate of 0.1 to 1.0 preferred. The reaction products are withdrawn from unit 25 through line 30 and thence discharged into a distillation tower 35, the operation of which will be more fully explained hereinafter.

Referring back to solvent extraction column 3 a fraction predominantly naphthenic or cyclo-

paraffinic in character containing, for example, compounds such as methylcyclohexane is withdrawn through line 48, part of which, if desired, may be returned to the tower as reflux through line 49. This product is heated in a furnace or other suitable heating means 45, thence discharged through line 47 into a flash tower 49 in which tower it is separated from solvent which is withdrawn through line 58. The naphthenic fraction is then discharged through line 52 into a dehydrogenator 55. Dehydrogenator 55 contains a catalyst which is preferably chromia or 3-30% of molybdenum oxide supported on Activated Alumina or magnesia. Other catalysts may be used such as the oxides of metals of the IV, V, and VI groups of the periodic system. This catalyst which may be in the form of pills, pellets, extruded lengths, etc., is preferably supported on a foraminous tray T', as indicated in the drawing. A temperature within the range of 800-1200° F., with 875-1100° F. preferred, is maintained within the dehydrogenation zone. The pressure may vary from atmospheric to 20 atmospheres. However, pressures of the order of atmospheric give better results from the standpoint of conversion but the amount of coke formation is greater. Consequently, we prefer to operate at pressures as high as 20 atmospheres in this zone and to circulate hydrogen from some suitable source through line 71 through the reactor during the dehydrogenation, because we have observed that the presence of hydrogen retards the formation of coke so that the catalyst may be used for a greater period of time without requiring regeneration. The amount of hydrogen should be from 2000-4000 cubic feet per barrel of oil. The hydrogen contained in the off gases in line 37 from distillation tower 35 is recycled via line 41 after passing through a scrubber 8 in which scrubber it is preferably treated with a hydrocarbon oil to dissolve out hydrocarbons and then recycled to line 71. The feed rate of naphthenic charging stock should be from 0.5-4 volumes of feed per volume of catalyst per hour on a cold oil basis.

The dehydrogenation product is withdrawn through line 58 and discharged into line 38 and thereafter into distillation tower 35.

Referring again to the solvent extraction column 3, the bottoms fraction which is rich in aromatic constituents is withdrawn through line 70, passed through a heat exchanger 72 where it is heated by heat interchange with recycle stock from reactor 25 and/or reactor 55, thence withdrawn through line 80 and discharged into a distillation zone 82 from which the aromatics may be withdrawn through line 85. The solvent is withdrawn from the bottom of zone 82 through line 108 and returned through line 5 to the top of extraction tower 3.

Nitration grade toluene can be prepared from the aromatic product discharged from distillation zone 82 through line 85 by simply acid treating and redistilling the fraction boiling between 228° F. and 231° F. Thus the product in line 85 containing aromatics will also contain some olefins, and we therefore treat the product with sulphuric acid in vessel 89 in order to polymerize the olefins, finally discharging them into a finishing still 90 where the polymerized olefins may be separated from the aromatics by distillation as an overhead product.

Referring back to the products in lines 30 and 60, respectively, the same may be, as indicated, discharged into distillation tower 35 by operation 75

of valve 31 or by manipulation of valve 61, or they may be in part at least recycled to fresh feed inlet line 1 for solvent extraction of their aromatic content produced in the cyclization and dehydrogenation steps. The recycle stream in line 62 may, as indicated, pass through heat exchanger 72 by manipulation of valves 63 and 65. Alternatively, the product in line 62 may be combined with the product in line 85 and passed directly to drum 82.

Referring again to distillation tower 35, the light gases which also contain large amounts of hydrogen may be withdrawn through line 37, and these may be recycled to either reactor 25 or reactor 55, or both. If desired, these gases may be further enriched in hydrogen by scrubbing with oil before being recycled. A C₆-C₈ hydrocarbon fraction may be withdrawn through line 39. Through line 38 aromatic-containing bottoms are withdrawn and delivered to line 62 from which they are preferably discharged with fresh feed into solvent treating tower 3 to dissolve out the aromatics. Alternatively, however, these aromatics originating in line 38 may be charged to stripping tower 82.

It will be understood that periodically, reactors 25 and 55 will require regeneration of the catalyst, and for this purpose the oil streams to the said reactors are shut off and the deposits on the catalyst caused by the reaction are consumed by burning preferably with air or other oxygen-containing gas. In order to provide continuity of operation two or more reactors of the type of 25 and 55 may be provided so that while the productive phase of the overall operation is proceeding in one of the reactors 25 and 55, the other or others may be undergoing regeneration of its catalyst.

It is also within the scope of our invention to employ instead of the pilled catalyst in reactors 25 and 55, where the catalyst is in the form of a stationary bed or beds, to employ catalyst in powder form suspended or fluidized by the vapors undergoing reaction, supplemented if necessary by other means. The precise details of operating the reactors and the solvent extraction zone do not per se form the essence of our invention.

While the above invention has described the preparation of toluene from a narrow cut hydrocarbon fraction, other narrow boiling fractions may be similarly treated. For example, large amounts of aromatics especially xylenes may also be obtained from hydrocarbons boiling between about 240 to 300° F. containing hydrocarbons such as octanes, ethyl cyclohexane, dimethylcyclohexanes and xylenes. The solvent may be phenol or some other solvent boiling at a temperature somewhat above the temperature at which the hydrocarbon feed is in the vapor state.

To recapitulate briefly, our invention resides in the concept of treating a narrow boiling hydrocarbon oil such as a cracked or virgin naphtha to solvent extraction wherein the naphtha, preferably in vapor form, is treated with a liquid solvent such as phenol, and in an extraction zone the charged stock is divided into relatively narrow boiling range aromatics, naphthenes, and paraffins, and after separation of the aromatics from the naphthenes and paraffins we propose to dehydrogenate the former and cyclize and aromatize the latter, combining these formed aromatics with the aromatics originally present in the feed stock and thus secure a high yield of aromatics.

Many modifications falling within the scope of

our invention will suggest themselves to those who are familiar with this art.

What we claim is:

1. An improved process for the production of nitration grade toluene from a hydrocarbon fraction containing paraffins, naphthenes and aromatics and boiling in the range between about 190° and 240° F. which comprises solvent extracting said hydrocarbon fraction with a liquid preferential solvent for aromatics at a temperature between about 200° and 220° F. in a solvent treating zone, withdrawing from said zone a hydrocarbon stream rich in paraffins, a hydrocarbon stream rich in naphthenes, and a hydrocarbon stream rich in aromatics, separately subjecting said paraffinic stream to aromatization in the presence of a catalyst selected from the group consisting of the oxides of chromium, molybdenum and vanadium, and in the presence of a recirculating stream of hydrogen maintained at a pressure between 50 and 300 lbs. per square inch, separately subjecting said naphthenic stream to hydroforming in the presence of a catalyst consisting of from 3 to 20% of molybdenum oxide supported on Activated Alumina, and in the presence of a recirculating stream of hydrogen maintained at a pressure between 50 and 300 lbs. per square inch, said hydrogen stream containing between 30 and 80 mol percent hydrogen, combining the products of aromatization and hydroforming, subjecting said combined products to vapor-liquid solvent extraction, removing from said solvent extraction an aromatic fraction, passing said aromatic fraction to a distillation zone, recovering from said zone a fraction boiling between about 228° and 231° F., washing the fraction boiling between about 228° and 231° F. with sulfuric acid to remove olefins, and redistilling to obtain thereby substantially pure toluene.

2. An improved process for the production of substantially pure xylenes from a hydrocarbon fraction containing paraffins, naphthenes and aromatics and boiling in the range between about 240° and 300° F. which comprises vaporizing said hydrocarbon fraction, subjecting the vaporized hydrocarbons to solvent extraction with a solvent in the liquid state, segregating thereby three fractions enriched respectively in paraffinic, naphthenic and aromatic constituents, separate-

ly subjecting said fraction enriched in paraffins to catalytic aromatization, separately subjecting said fraction enriched in naphthenes to catalytic dehydrogenation in the presence of a stream of hydrogen, combining the products of aromatization and dehydrogenation boiling in the range between about 240° and 300° F. and subjecting the combined products to solvent extraction in the said solvent extraction zone, removing from said solvent extraction zone an extract phase enriched in xylenes, stripping said extract phase of extract to obtain a stream of hydrocarbons containing substantially only xylenes, acid treating said stream of hydrocarbons containing said xylenes, subjecting the products of acid treating to distillation, and removing therefrom substantially pure xylenes.

3. The improved process according to claim 2 in which hydrogen is present in the aromatization zone in an amount between about 1000 and 4000 cubic feet per barrel and in which a pressure between about 50 and 400 lbs. per square inch pressure is improved on the system.

4. An improved process for the production of substantially pure xylenes from a hydrocarbon fraction containing paraffins, naphthenes and aromatics and boiling in the range between about 240° and 300° F. which comprises vaporizing said hydrocarbon fraction, subjecting the vaporized hydrocarbons to solvent extraction with a solvent in the liquid state, segregating thereby three fractions enriched respectively in paraffinic, naphthenic and aromatic constituents, separately subjecting said fraction enriched in paraffins to catalytic aromatization, separating subjecting said fraction enriched in naphthenes to catalytic dehydrogenation in the presence of a stream of hydrogen, combining the products of aromatization and dehydrogenation boiling in the range between about 240° and 300° F. and subjecting the combined products to solvent extraction in the said solvent extraction zone, removing from said solvent extraction zone an extract phase enriched in xylenes, and stripping said extract phase of extract to obtain a stream of hydrocarbons containing substantially only xylenes.

our invention will suggest themselves to those who are familiar with this art.

What we claim is:

1. An improved process for the production of nitration grade toluene from a hydrocarbon fraction containing paraffins, naphthenes and aromatics and boiling in the range between about 190° and 240° F. which comprises solvent extracting said hydrocarbon fraction with a liquid preferential solvent for aromatics at a temperature between about 200° and 220° F. in a solvent treating zone, withdrawing from said zone a hydrocarbon stream rich in paraffins, a hydrocarbon stream rich in naphthenes, and a hydrocarbon stream rich in aromatics, separately subjecting said paraffinic stream to aromatization in the presence of a catalyst selected from the group consisting of the oxides of chromium, molybdenum and vanadium, and in the presence of a recirculating stream of hydrogen maintained at a pressure between 50 and 300 lbs. per square inch, separately subjecting said naphthenic stream to hydroforming in the presence of a catalyst consisting of from 3 to 20% of molybdenum oxide supported on Activated Alumina, and in the presence of a recirculating stream of hydrogen maintained at a pressure between 50 and 300 lbs. per square inch, said hydrogen stream containing between 30 and 80 mol percent hydrogen, combining the products of aromatization and hydroforming, subjecting said combined products to vapor-liquid solvent extraction, removing from said solvent extraction an aromatic fraction, passing said aromatic fraction to a distillation zone, recovering from said zone a fraction boiling between about 228° and 231° F., washing the fraction boiling between about 228° and 231° F. with sulfuric acid to remove olefins, and redistilling to obtain thereby substantially pure toluene.

2. An improved process for the production of substantially pure xylenes from a hydrocarbon fraction containing paraffins, naphthenes and aromatics and boiling in the range between about 240° and 300° F. which comprises vaporizing said hydrocarbon fraction, subjecting the vaporized hydrocarbons to solvent extraction with a solvent in the liquid state, segregating thereby three fractions enriched respectively in paraffinic, naphthenic and aromatic constituents, separate-

ly subjecting said fraction enriched in paraffins to catalytic aromatization, separately subjecting said fraction enriched in naphthenes to catalytic dehydrogenation in the presence of a stream of hydrogen, combining the products of aromatization and dehydrogenation boiling in the range between about 240° and 300° F. and subjecting the combined products to solvent extraction in the said solvent extraction zone, removing from said solvent extraction zone an extract phase enriched in xylenes, stripping said extract phase of extract to obtain a stream of hydrocarbons containing substantially only xylenes, acid treating said stream of hydrocarbons containing said xylenes, subjecting the products of acid treating to distillation, and removing therefrom substantially pure xylenes.

3. The improved process according to claim 2 in which hydrogen is present in the aromatization zone in an amount between about 1000 and 4000 cubic feet per barrel and in which a pressure between about 50 and 400 lbs. per square inch pressure is improved on the system.

4. An improved process for the production of substantially pure xylenes from a hydrocarbon fraction containing paraffins, naphthenes and aromatics and boiling in the range between about 240° and 300° F. which comprises vaporizing said hydrocarbon fraction, subjecting the vaporized hydrocarbons to solvent extraction with a solvent in the liquid state, segregating thereby three fractions enriched respectively in paraffinic, naphthenic and aromatic constituents, separately subjecting said fraction enriched in paraffins to catalytic aromatization, separating subjecting said fraction enriched in naphthenes to catalytic dehydrogenation in the presence of a stream of hydrogen, combining the products of aromatization and dehydrogenation boiling in the range between about 240° and 300° F. and subjecting the combined products to solvent extraction in the said solvent extraction zone, removing from said solvent extraction zone an extract phase enriched in xylenes, and stripping said extract phase of extract to obtain a stream of hydrocarbons containing substantially only xylenes.
